UNITED STATES PATENT OFFICE

162,753

COMBINED SOAP HOLDER AND BRUSH

Robert C. Runyon, Springfield, N. J.

Application November 22, 1949, Serial No. 6,190

Term of patent 3½ years

(Cl. D9—2)

To all whom it may concern:

Be it known that I, Robert C. Runyon, a citizen of the United States, residing at Springfield, county of Union, and State of New Jersey, have invented a new, original, and ornamental Design for a Combined Soap Holder and Brush, of which the following is a specification, reference being had to the accompanying drawing, forming part thereof, in which,

Fig. 1 is a side elevational view of a combined soap holder and brush, showing my new design;

Fig. 2 is an end elevational view thereof;

Fig. 3 is a top plan view thereof; and

Fig. 4 is a bottom plan view thereof.

I claim:

The ornamental design for a combined soap holder and brush, as shown.

ROBERT C. RUNYON.
